PAUL ROHRIG, OF BELLAIRE, NEW YORK, ASSIGNOR TO PNEUMATIC SCALE CORPORATION, LTD., OF NORFOLK DOWNS, MASSACHUSETTS, A CORPORATION OF MASSACHUSETTS

STRING WINDING DEVICE FOR BAGGING MACHINES

Application filed May 27, 1929. Serial No. 366,132. Filed 100

The present invention comprises a string winding device of particular value as an attachment to known machines for making and tagging tea cartridges, although susceptible of advantageous use whenever it is desired to automatically wind string around a member. The device when used as an attachment to tea bag machines eliminates the operation heretofore manually performed of winding 10 about the completed cartridge the string carrying the tag, in order that the cartridges may be packed in and removed from cartons without entangling the strings one with another.

There are now in use numerous automatic machines for producing tea cartridges, or balls, which are provided with means for automatically fastening a short length of string to the neck of the bag and for applying a tag or handle to the free end of the string. Other machines are in use which perform the latter operations only. Still other machines fill and form the cartridges and apply a metallic split circlet, to which the tagged 25 string has been manually attached, to the neck of the cartridge.

The finished product from such machines is packed in cartons for delivery, usually at least six cartridges being packed together in 30 each carton. Before packing, it is necessary, in order to permit separate removal of the cartridges, that the tagged string of each be closely wrapped around the cartridge, and this has heretofore been done manually, usually 35 at least two operators being necessary to each machine. By means of the invention this manual operation is eliminated, and the cartridges delivered ready for immediate packing.

The present device is of simple construction and may be readily and economically added to the machines now in use without substantial modification of their construction or any interference with their usual operation.

For a better understanding of the invention, reference should be had to the accompanying drawings in which:

Fig. 1 is a side view partly in section of 50 the preferred embodiment of the invention;

Fig. 2 is a perspective enlarged view, partly in section, of the winding device; and

Fig. 3 is a view of a tea cartridge after delivery from a machine provided with the device.

Machines of the type with which the device is adapted to be used comprise a frame, the upper portion of which forms a table 1 over which, in a horizontal plane, a plurality of radially disposed gripping jaws 2 are intermittently rotated about a central point, by means of suitable cams and gearing (not shown) from a main drive shaft 3. Jaws 2 carry the cartridge 4 while the various operations of bag forming, tea filling, string and label attaching are performed, and are finally opened to discharge the completed cartridge. Only so much of the various mechanisms by which these operations are performed as are essential for understanding the operation of the device, are illustrated herein, for they form no part of the present invention, and their particular construction is immaterial to the practice of the invention.

The string winding device is shown at 5. It is mounted upon the frame 1 below the path of movement of the outer end of the jaws 2, and in a position over which the jaws are adapted to pass just prior to their opening movement for discharge of the cartridge from the machine. This device 5 comprises a cylindrical metal member provided along the outer surface of its upper end with a number of longitudinal grooves 6. Groups of stiff bristles or the like 7 are located in the grooves 6 and are there held in place by a binding ring 8. The device 5 is rotatably and slidably mounted on a rod 9, the lower end of which is screw-threadedly mounted on the frame 1, and the upper end of which carries a disk 10 having a diameter slightly smaller than the internal diameter of the cylindrical portion of device 5.

Device 5 is continuously rotated by a belt 11 resting in an annular groove 12 in the lower portion of the device and driven by a pulley 13 mounted on shaft 14. Shaft 14 may be driven in any suitable manner, as by bevel gears 15, from the main drive shaft 3 of the machine. An arm 16, pivotally mounted 95

on frame 1, when rocked about its pivot, serves to lift device 5 into the position shown in dotted lines in Fig. 1 and in full lines in Fig. 2, by means of a forked member 17 attached to arm 16 and carrying rollers (not shown) adapted to rest in an annular groove 18 on device 5. Any suitable means may be employed for rocking arm 16 immediately after jaws 2 have brought the tea cartridge over device 5, as by a member 19 in contact with the end of arm 16, adapted to intermittently bear down thereupon. When the device is used in connection with the type of machine which applies the label and thereafter cuts the string beyond the label, member 19 may conveniently be mounted on the string cutting mechanism. Release of arm 16 by member 19 permits the device to be lowered by gravity.

The operation of the apparatus above described is as follows: After jaws 2 have brought the completed cartridge over the winding device, the latter is raised by arm 16 into the position where the cylindrical portion surrounds the cartridge, as shown in Fig. 2. The string 20 is then caught by the bristles 7, or between adjacent groups thereof, and wound about the cartridge by the rotation of device 5. The bristles, being yieldable, do not catch and tear the label from the string, but permit the same to be drawn up to the cartridge by the winding of the string.

Upon the completion of the winding operation, member 19 releases arm 16, permitting device 5 to descend by gravity out of the path of the cartridge, and jaws 2 thereupon move to the discharge position of the machine. The cartridge, when delivered, is ready for immediate packing, with the tagged string neatly wound thereabout, as shown in Fig. 3.

When the device is employed with the type of machine which applies the label to a taut string and thereafter cuts the string beyond the label, it is preferable to provide a pair of shields 21 and 22, as shown in Fig. 1, suitably mounted to a fixed part of the machine, to prevent the rebound of the string, when cut, from throwing it around the jaws 2, or around the cartridge prior to the raising of device 5. It is also preferable to provide the cylindrical portion of device 5 with a series of apertures 23 to prevent accumulation of any particles of tea which may sift through the gauze of the cartridge during the winding operation.

The above described embodiment of the invention is a preferred form for use as an attachment to tea bag machines. It is to be understood, however, that the invention is not limited to such use, as the device may be advantageously employed wherever it is desired to wind string about a member, whether or not a label is attached to the string, and whether or not the member about which the string is wound is a cartridge containing tea. It is preferable to utilize bristles or similar

yieldable means to catch and wind the string, but such yieldable means are not essential to the device except when the string has attached thereto a tag or label at the free end.

I claim:

1. A string winding attachment for bag machines comprising a hollow cylindrical member vertically positioned with reference to its axis and provided at its upper periphery with vertically projecting yieldable members, means for continuously rotating said cylindrical member about its axis, and means for vertically raising the same during the rotation thereof into a position where said yieldable members may catch the string of the bag therebetween. 70

2. In combination with means for holding a tea cartridge having an attached string, an attachment for winding the attached string about the cartridge comprising a device 85 adapted when in one position to yieldably catch the string, means for moving said device into said position, and means for rotating said device.

3. In combination with means for holding a member having one end of a string attached thereto, a device for winding the string about said member comprising a cylindrical element adapted to be positioned about said member and provided at its upper end with means for 95 slidably holding said string, and means for rotating said element.

4. The combination according to claim 3 wherein said holding means comprised spaced groups of bristles or the like. 100

5. The combination with means for holding a tea bag, of a hollow string winding member capable of being moved over the bag, and provided with means for slidably engaging the string, means for moving the 105 winding member into and from operative position, and means for rotating the winding element while in operative position.

6. The combination with a holding device for holding the neck portion of a tea bag, of 110 a string winding member provided with means for slidably engaging the string, and being movable into and from a position which upon rotation is adapted to effect the winding of the string about the neck portion of the tea bag, and means for rotating the winding element while in such position.

7. The combination with means for holding a tea bag, of a spring winding element comprising a hollow member provided upon 120 its periphery with a plurality of yieldable members for slidably engaging the string, means for rotating the hollow member, and means for moving the hollow member toward and from the bag holding member.

8. The combination with means for holding a filled bag having a handle including a flexible member attached at one end to the neck of the bag and projecting for a substantial distance therefrom, of mechanism for 125

winding up substantially the entire projecting portion of the flexible member, around the neck of the bag for purposes of shipment including a member for engaging said handle during the entire winding operation, and means for effecting relative rotation of said member and the bag holding means.

9. The combination with means for holding a filled bag having a handle including a flexible member attached at one end to the neck of the bag and projecting for a substantial distance therefrom, of mechanism for winding up substantially the entire projecting portion of the flexible member, around the neck of the bag for purposes of shipment including a rotatable member for engaging and winding the flexible member about the neck of the bag and means for effecting rotation of said rotatable member.

10. The combination with means for holding a filled bag having a handle including a flexible member attached at one end to the neck of the bag and projecting for a substantial distance therefrom, of mechanism for winding up substantially the entire projecting portion of the flexible member, around the neck of the bag for purposes of shipment including a rotatable member movable into and out of operative position and arranged when in operative position to engage said flexible member and wind it about the neck of the bag.

In testimony whereof, I have signed my name to this specification.

PAUL ROHRIG.
